UNITED STATES PATENT OFFICE.

BENNETT D. STRAIGHT, OF DETROIT, MICHIGAN, ASSIGNOR TO MAIL-OM-ETER COMPANY, OF DETROIT, MICHIGAN, A CORPORATION OF MICHIGAN.

STAMP-AFFIXING MACHINE.

1,203,932.

Specification of Letters Patent.

Patented Nov. 7, 1916.

Application filed December 27, 1909. Serial No. 535,113.

To all whom it may concern:

Be it known that I, BENNETT D. STRAIGHT, a citizen of the United States of America, residing at Detroit, in the county of Wayne 5 and State of Michigan, have invented certain new and useful Improvements in Stamp-Affixing Machines, of which the following is a specification, reference being had therein to the accompanying drawings.

10 The invention relates to stamp affixing machines of that type in which the stamps are fed in a continuous strip, and are successively severed from the strip and affixed to the envelop or other surface to which they 15 are to be applied.

The invention consists in the means employed for feeding the stamps, the means for severing the stamps, means whereby the severing operation also applies the same, 20 means for moistening the surface to which the stamps are applied, and, further, in the peculiar construction, arrangement and combination of parts, as hereinafter set forth.

In the drawings: Figure 1 is a vertical longitudinal section through an end-operated stamp affixer constructed in accordance with my invention; Fig. 2 is a similar view showing the parts in a different position of adjustment; Fig. 3 is a detached perspective 30 view illustrating the feeding device; Fig. 4 is a vertical central section through the feeder; and Figs. 5 and 6 are enlarged sectional views of a portion of Fig. 2 illustrating the operation.

35 One difficulty encountered in the construction of stamp or label-affixing mechanism is the variation in width of the different stamps or labels due to the expansion and contraction of the paper, and to other causes.

40 Thus, where the severing of the stamps is effected by a blade, it is necessary to provide a complex feed mechanism to correctly position the successive stamps for severing, and even where this is done, it is difficult to 45 obtain a perfect registration, and often the cutting is at one side of the exact line of division. With my invention, this difficulty is overcome by tearing the stamps from the strip, which dispenses with the necessity of 50 absolute uniformity in registration; further, by effecting the tearing by clamping the strip upon opposite sides of the weakened line of the perforations and then pressing laterally upon the intermediate portion to 55 effect the rupture.

In the specific construction shown, A is a frame, in which is slidably secured a plunger B, provided at its upper end with an operating handle C.

D is a holder for a strip of stamps or 60 labels, which are preferably in the form of a roll engaging a pin D'.

E is a guide-way for the stamps extending downward from the holder D, and F is a feeder actuated by the plunger B and operated to advance the stamp strip along the guide E. The feeder F may be of any suitable construction so long as it feeds the stamps at the proper time to the separating and applying mechanism hereinafter 65 described. The construction of feeding mechanism which I have herein shown comprises a slide-block F' engaging guide-ways E⁴ on the opposite sides of the stamp-guide E, this stamp guide being located so that the stamps 70 will feed from the roll vertically down beside the plunger. The stamps are preferably pressed against the stamp-guide by springs E'.

The stamps are fed downward by a friction-pawl G, pivoted to the slide-block F' at G' and having a friction surface, such as leather or rubber, as shown at a. The slide-block F' is connected by links H H' with the plunger B, the location of the pivots of the 80 connection being such that as the plunger moves downward it will rock the pawl G upon its pivot and throw the friction-face a into contact with the stamp-strip and feed the same downward; but, in the upward 85 movement of the plunger, the friction-face will be rocked away from contact with the strip and move upwardly free therefrom.

In addition to the friction-pawl G for moving the stamp-strip downward at each 90 downward movement of the plunger, I provide a series of pointed pawls I, yieldingly pressed by springs I' against the paper strip, the points being so constructed that they will engage with the perforations between adjacent stamps when registered therewith. These pawls are pivoted at the lower ends at b upon the slide-block F' and at their upper ends project over a cross-bar J on the rocking frame J'—which is likewise pivoted upon the pivot b. This rocking frame has lateral extensions J² which project into contact with the guides E⁴ which are provided with the cams E², these cams moving the pointed pawls into and 100 105 110

out of engagement with the stamp-strip as the plunger moves the slide-block up and down.

The whole organization of the feed mechanism is such that in the downward movement of the plunger the friction-pawl will engage and feed the stamp strip downward but be held out of contact therewith during the upward movement.

10 Near the upper end of the upward movement of the slide-block the lateral extensions J^2 will ride down the cam-ways E^2 , when the pawls I , through the medium of the pawls and the cross-bar, will be forced into 15 contact with the stamp strip, engaging the perforations as shown in Fig. 3, and move the stamp-strip upward or downward to a definite position. Thus the position of the strip is corrected in case there is any difference 20 in the size of the stamps or in case there should be a minute slippage of the pawl in feeding the stamp-strip down, so that upon each succeeding operation the friction-pawl will engage with a properly 25 registered strip and advance it to a distance equal to the width of one stamp.

The stamp strip is directed by the guide E to the lower end of the frame A , and at that point a curve E^3 in the guide will project 30 the free end of the strip in a horizontal direction and only slightly above the plane of the envelop or surface to which the stamp is to be affixed. At this point, the end stamp is severed and applied by mechanism 35 of the following construction: K is a foot which is depressed by the movement of the plunger B and which is adapted to clamp the outer end portion of the strip against the surface to which it is to be applied and 40 also clamp the strip to the curved portion of the guide above the weakened line of division of the stamp to be severed. The foot is further provided with a severing section for rupturing the strip along the weakened line intermediate the portions at which the stamp is clamped, the foot being so constructed and arranged relative to the plunger B that in the downward movement of the latter the severing portion of the foot 45 will not be actuated until the strip has first been clamped upon opposite sides of the weakened line. As shown, the foot comprises an open centered frame K^2 within which is arranged the rupturing member M pivoted thereto at M' . K' are links arranged upon opposite sides of the frame K^2 , each of which has its opposite ends secured to the pivot M' and to the frame A respectively. The foot is yieldably attached to 50 the plunger by a spring L pivotally secured at one end to the plunger and having its opposite end slidably engaging an eye L' upon the upper face of the member M . This spring will draw the foot upward when the 55 plunger is retracted, but in the downward

movement of the plunger the foot will not be depressed until the lower end of the plunger engages the upper face of the member M . This latter member is normally held in fixed relation to the frame (as shown in Fig. 5) by means of springs M^2 , and these springs are of sufficient tension to prevent depression of the rupturing member during the initial depression of the foot. When the member K^2 has reached the limit of its 75 downward movement the portion of the member M adjacent its pivotal connection clamps the outer end of the strip to the article to be stamped, and the end M^2 of the frame K^2 engages the strip beyond the 80 weakened line of severance and clamps the same to the curved portion of the guide. A further downward movement of the plunger will depress the inner end of the member M independent of the frame K^2 , this will rupture the strip along the weakened line intermediate the portions at which the strip is clamped.

The moistening of the gummed surface of the stamp is preferably effected by drawing a moistened pad over the surface of the envelop just in advance of the feeding of the stamp, and the severing and application of the same. For this purpose, the machine is provided with a moistening pad N , which is mounted upon a rockable and slidable bearing O . The member O is provided with trunnions O' , which engage horizontal guide slots O^2 in the frame A . 90

P is a swinging link fulcrumed to the frame at its upper end, and at its lower end connected through the intermediate link P' with the member O .

Q is a link connected at one end to the plunger B , and at its opposite end to the link P intermediate its fulcrum and the point of connection with the link P' .

The construction is such that, in normal position of the parts, where the plunger is raised, the pad N will occupy a position 105 slightly above the envelop, and at a point where the stamp is to be applied. When the plunger is depressed, the link Q will swing the link P , and through the medium of the link P' will carry the member O and pad N rearward, but, before this movement is imparted to the pad, the member O will be tilted by the action of the links, so that the moistened surface of the pad will contact with the paper. Thus, during the rearward movement, the surface of the paper will be moistened by the pad, and, when the stamp is subsequently pressed in contact with this moistened surface, it will adhere thereto. Upon the return movement of the links Q , P and P' , their initial action will be to tilt the member O , so as to withdraw the pad from contact with the surface, and avoid wetting it a second time. 110

My machine is preferably provided with 115

various specific features for facilitating the operation of the same. One of these, is the means employed for disengaging the stamp guide to permit of threading a stamp strip therewith. For this purpose, the holder D is pivotally attached at D² to the frame A, and the link which attaches the slide F' to the plunger B is formed of the normally folded sections H H'. Thus, the holder D 10 may be swung outward upon its pivot D², straightening out the folded sections H H' and bringing the guide E into a position where it is accessible for the insertion of the stamp strip.

15 Another specific feature of my machine is the means employed for stopping the feeding of the strip during the severing operation, while still actuating both devices from the plunger B. This consists of a collar R upon 20 the plunger B, to which the link H is connected, and a latch bolt S for coupling said collar to the plunger. The latch bolt S is normally held in engagement with the plunger by a spring S' operating upon a 25 bell-crank lever S² attached to bolt. The outer end of this bell-crank lever has an eye loosely engaging a rod T upon the frame, while at the lower end of said rod is a head or collar T' for tripping the bell-crank lever 30 at a certain point in the movement of the plunger. This tripping is effected at the completion of the feeding of the stamp strip, and, as soon as the collar is disengaged, the plunger is free to travel farther to complete 35 its operation without further actuating the feeder F.

What I claim as my invention is:—

1. In a stamp or label affixing device, the combination of a reciprocatory plunger, a feeder for the strip of stamps or labels actuated by said plunger, a foot carried by said plunger for clamping said strip at the termination of the feeding movement thereof, said foot having a movable section for pressing on said strip subsequent to the clamping thereof, and means for automatically uncoupling said feeder and foot from said plunger to permit the further movement of the latter and the actuation of said independently movable foot section thereby.
2. In a stamp and label affixing device, the combination with a frame, a reciprocatory plunger mounted therein, a member having a latch-coupling engagement with said plunger, a feeder and a clamp actuated from said plunger through the medium of said member thereon, means operating at the completion of the feeding movement for unlatching said coupling, said clamp having a portion subsequently operated directly by said plunger for rupturing the stamp strip and pressing the same against the surface to be stamped.
3. In a stamp or label affixing device, a plunger for controlling the stamp affix-

ing, stamp strip feeding and stamp severing means actuated by the forward movement of the plunger, means for disconnecting the stamp feed before the plunger completes its forward movement, and a clamp 70 for the stamp strip applied during the forward movement of the plunger while the stamp feed is disconnected.

4. In a stamp or label affixing device, the combination of a stamp holder, a vertical 75 guide from the holder for the stamp strip, a reciprocatory plunger beside the guide for controlling the stamp affixing, a strip feed carried by the plunger engaging the strip in the vertical guide, and feeding it forward 80 in the downward movement of the plunger, and means for disconnecting the strip feed before the plunger reaches the limit of its motion.

5. In a stamp or label affixing machine, 85 the combination of a strip holder, a vertical guide leading therefrom, a reciprocatory plunger for controlling the stamp affixing arranged beside the guide, and a series of fingers carried by the plunger adapted to 90 engage perforations in the strip in its downward movement to feed the strip forward.

6. The combination with a reciprocating plunger for controlling the stamp affixing and a stamp feed actuated in the inward 95 movement thereof, of means actuated by the plunger for engaging the stamp strip perforations before the end of the upward movement, to move such perforations to a fixed point at each operation.

7. The combination in a machine for feeding a stamp-strip and severing and applying a stamp, of a reciprocating plunger for controlling the stamp affixing, a stamp feed actuated by the plunger in its inward movement to feed the stamp-strip forward, means for disengaging the stamp-feed from the plunger before the end of inward movement thereof, and means for engaging the perforations of the stamp-strip before the end 110 of the return movement of the plunger, to move such perforations to a fixed point at each operation.

8. The combination with a reciprocatory plunger for controlling the stamp affixing, 115 of a stamp feed actuated thereby comprising means for automatically engaging and moving the stamp-strip in the downward movement of the plunger and being released and moving free therefrom in the upward movement, and means for engaging the stamp-strip perforations before the end of the upward movement to move such perforations to a fixed point at each operation.

9. In a stamp affixer, the combination 125 with a frame, of a plunger, an affixing member actuated thereby, a reciprocatory stamp feeding mechanism, a collar carried by said plunger for moving the feeding mechanism with said plunger, and means for rendering 130

- said collar loose upon the plunger, at a certain point of its downward motion, and retaining it against participation in the further downward movement of the plunger.
- 5 10. In a stamp affixer, the combination with a frame, of a plunger mounted in said frame, a stamp affixing member having a swinging connection with the frame and with the plunger and actuated by the latter,
- 10 and a stamp feeding mechanism actuated by the plunger.
11. The combination with a strip-feeding

mechanism, of an affixing member comprising clamping and rupturing parts, a plunger for actuating said member, and a swinging connection between the plunger and said member. 15

In testimony whereof I affix my signature in presence of two witnesses.

BENNETT D. STRAIGHT.
